UNITED STATES PATENT OFFICE.

ROBERT B. WATSON AND JESSE C. KITTERMAN, OF CORYDON, INDIANA.

FLY-EXIT FOR SCREEN DOORS AND WINDOWS.

1,314,774.

Specification of Letters Patent.

Patented Sept. 2, 1919.

Application filed September 23, 1918. Serial No. 255,321.

To all whom it may concern:

Be it known that we, ROBERT B. WATSON and JESSE C. KITTERMAN, citizens of the United States, residing at Corydon, in the 5 county of Harrison, State of Indiana, have invented certain new and useful Improvements in Fly-Exits for Screen Doors and Windows; and we do hereby declare the following to be a full, clear, and exact description 10 of the invention, such as will enable others skilled in the art to which it appertains to make and use the same.

This invention relates to new and useful improvements in fly exits and particularly 15 to fly exits for window and door screens.

One object of the present invention is to provide a novel and improved device of this character wherein provision is made whereby the flies, when crawling upwardly on the 20 screen fabric can be trapped in compartments from which they cannot reenter the house.

Another object is to so construct a door or window of this class whereby the flies 25 can escape only to the outside, from the trapping compartments.

Other objects and advantages will be apparent from the following description when taken in connection with the accom- 30 panying drawing.

In the drawing:

Figure 1 is an elevation, partly broken away, of a screen door made in accordance with our invention.

Fig. 2 is a vertical longitudinal sectional view through the door, taken in a plane parallel to the face of the door.

Fig. 3 is a vertical longitudinal sectional view taken on the staggered line 3—3 of Fig. 1, showing the exit openings of the arcuate screen strips.

Fig. 4 is a horizontal sectional view taken on the line 4—4 of Fig. 1.

Fig. 5 is a horizontal sectional view taken 45 on the line 5—5 of Fig. 1.

Referring particularly to the accompany- 50 ing drawing, 10 represents a screen door frame which has secured thereto the usual wire screen fabric 11. The lower portion of the door is divided by means of the trans- 55 verse rail 12 and the vertical rail 13. The screen fabric is preferably secured to the outer face of the door for the purpose of the successful operation of the invention. Secured to the inner faces of the upper rail 14, and the side rails 15, of the door, and

extending across approximately one-third of the upper section of the door is a sheet or wire screen 16, the same being thus spaced from the outer screen to a distance equaling 60 that of the thickness of the rails. An arcuate strip of screen 17 is disposed between the screen 11 and the screen 16 and has its ends secured to the inner side faces of the side rails 15, with its convex face 65 directed upwardly. The edges of this strip, are in firm contact with the inner faces of the screens 11 and 16, so that there will be no spaces for the flies to pass therebetween. However, to permit the flies to get into the 70 space between the arcuate strip and the top rail of the door, there are cut the notches 18 in the opposite edges of the upper portion of the strip. Formed in the outer face of the rail 14 and communicating with the 75 space thus described, are the grooves 19, through which the flies escape to the outside of the door. The screen retaining strip 20 covers, or bridges over, the lower portions of these grooves to prevent entrance of the 80 flies.

Similarly secured to the lower portion of the door, and covering the upper part, below the cross rail 12, is a sheet of screen fabric 21. Arcuate strips of screen 22 are 85 secured between the screens 11 and 21, in the same manner as the strip 17, with the convex faces directed upwardly. Each of the strips 22 is formed with the opposite exit notches 23, in the upper portion thereof, 90 in the same manner and for the same purpose as the notches 18. In the outer face of the transverse strip or rail 12 there are formed the grooves 24 which communicate with the lower compartments of the door, 95 formed by the side rails 15, the rail 12 and the rail 13, to permit the flies to escape to the outside.

It is well known that flies crawl upwardly in their efforts to escape, in so doing, they 100 will pass through the notches 18 or 23 into the spaces above the arcuate strips. By reason of this habit of the flies they will not crawl downwardly into the house again, but will finally find an exit to the outside 105 through the grooves.

This invention may readily be applied to any ordinary screen door by the attachment of the auxiliary screen members and the arcuate strips, the only modification to the 110 door being the cutting of the grooves. This the cost of the manufacture will not exceed

that of the ordinary screen door to any appreciable extent.

What is claimed is:

A screen door including a frame, wire screen covering the outer face of the door, wire screens partially covering the inner face of the door, arcuate strips of screen disposed between the inner and outer screens and coöperating with portions of the frame 10 to form compartments, the opposite edge portions of the arcuate strips having notches, the upper portion of the frame hav-

ing exit grooves and the transverse middle rail of the frame having grooves communicating with the said compartments and the 15 outside of the door.

In testimony whereof we affix our signatures in the presence of two witnesses.

ROBERT B. WATSON.
JESSE C. KITTERMAN.
